US00D575343S

(12) **United States Design Patent**
Cetera

(10) **Patent No.:** **US D575,343 S**
(45) **Date of Patent:** **** Aug. 19, 2008**

(54) **PEN GRIP**

(75) Inventor: **Carl Cetera**, Tenafly, NJ (US)

(73) Assignee: **Cotapaxi Custom Design and Manufacturing, LLC**, Carlstadt, NJ (US)

(**) Term: **14 Years**

(21) Appl. No.: **29/248,536**

(22) Filed: **Aug. 21, 2006**

(51) LOC (8) Cl. **19-06**

(52) U.S. Cl. **D19/55**

(58) Field of Classification Search **D19/35, D19/36, 41, 42, 43, 44, 45, 46, 47, 48, 49, D19/50, 51, 54, 55, 56, 57; 24/11 R, 11 F, 24/11 P; 40/334; 401/52, 99, 100, 104, 105, 401/106, 107, 108, 109, 192, 195, 196**

See application file for complete search history.

(57) **CLAIM**

The ornamental design for a pen grip, as shown and described.

DESCRIPTION

FIG. 1 is front side bottom perspective view of the pen grip showing my new design;

FIG. 2 is a left side elevation view thereof which is a mirror image of the right side thereof;

FIG. 3 is a bottom plan view thereof; and,

FIG. 4 is a top plan view thereof.

The broken lines depicting environmental structure are for illustrative purposes only and form no part of the claimed design.
